UNITED STATES PATENT OFFICE.

JOHN F. CUNNINGHAM, OF SAN FRANCISCO, CALIFORNIA.

ADVERTISING DEVICE.

1,081,021.

Specification of Letters Patent.

Patented Dec. 9, 1913.

Application filed November 16, 1907. Serial No. 402,567.

To all whom it may concern:

Be it known that I, JOHN F. CUNNINGHAM, a citizen of the United States, and a resident of the city and county of San Francisco, in the State of California, have invented a new and useful Advertising Device, of which the following is a specification, reference being had therein to the accompanying drawing.

10 This invention contemplates the use of a clock as an improved advertising medium. It is chiefly concerned with outdoor clocks, such as have been heretofore mounted on posts and allowed to be maintained at the 15 outer edge of sidewalks in some cities and towns, the same constituting what may be termed landmarks intended to indicate the location of certain business places, and consequently to draw public attention to the 20 same.

Sidewalk clocks mounted in the manner aforesaid have come to be regarded as unwarranted obstructions, and on that account are barred out of many localities, by adverse 25 municipal ordinances. Furthermore, wherever their use is still permitted, by sufferance or otherwise, it is acknowledged that after all they do not attract a great deal of attention, probably because as a rule they 30 are placed overhead to one side of the walks, too high above the throngs that pass by to command everybody's notice.

It is the purpose of the present invention 35 so to locate, position, and fit up the sidewalk-clock that not the least objection could be raised against it, either on the score of being an obstruction or for failure to gain an adequate and gratifying share of the 40 public's attention, thereby adapting it evidently for the discharge of its function as an advertising device.

In the drawing, Figure 1 is a top view showing a sidewalk-clock embodying one 45 form of this invention; Fig. 2 is a vertical transverse section on the line A—A of Fig. 1; and Fig. 3 is a bottom plan of the same.

The clock, for the purpose of this invention, is to be lodged in the sidewalk itself, with its face turned upward and the usual 50 plate glass over its dial set flush with the surface of the walk. The latter, herein designated by the numeral 1, is accordingly opened to provide a suitable aperture, as at 2, which may be circular as shown or of 55 any other desirable shape, and sufficiently large to permit the installation of a good

sized time-piece and its accessories. The aperture 2 is preferably lined with metal, cast-iron for instance, forming a curb 3 therein, designed to keep in its place the 60 surrounding cement, concrete, stone or brickwork, or other material from which the sidewalk 1 is constructed. An inwardly-projecting flange 4 is provided around the inner periphery of the curb 3, near the upper margin thereof, and upon it, is placed the outer covering 5 of the clock, which covering this invention admits of being made of highly transparent glass, such as French plate. A ring 6, which may be of wood, is 70 also fitted to the inner periphery of the curb, directly under the flange 4, and the same is made to extend up the flange, and for a short distance on a level therewith under the glass 5, as best seen in Fig. 2, both the flange and 75 the ring being beveled, as at 7, to facilitate the fitting. This ring affords a further support for the glass, and, through a series of recesses 8 cut out of its lower inner edge, provides for the indirect transmission of 80 light past the clock thereunder, as will presently be understood.

The clock's dial, 9, carrying the hour and minute hands, 10 and 11, on its upturned face, is secured by its edge to the under side 85 of the ring 6, which holds the dial spaced from the glass thereover enough to insure perfect freedom of movement for the hands, and sufficiently remote also from the inner circumference of the curb to avoid covering 90 the light-transmitting recesses 8. This dial, it will be inferred, is opaque as in ordinary clocks. From the center of the dial is suspended a small case 12 that contains the 95 works or movement, which may be of any desired manufacture, but by preference will be electrically connected for regulation at fixed intervals from some observatory, so as to show the correct time practically always, as the words "observatory time" inscribed on the face of the dial indicate.

It will now be seen that while it affords means for displaying a clock or clock dial conspicuously in the surface of a sidewalk for advertising purposes, the construction 105 above described provides also a vault-light, in so far as the glass-covered aperture with in which the advertising object is displayed transmits the light from the exterior to any subjacent vault, cellar, or basement that 110 the sidewalk may overlie, the light passing from above the dial 9 laterally and down-

wardly through the recesses 8 in the ring 6. The volume of light, of course, will be proportionate to the transparency of the glass plate, its dimensions, and the number of recesses or cut-away portions in the ring, but, though indirectly transmitted, the light, with judicious management, should be as ample, if not more so, than what is supplied through the ordinary translucent vault-covering. At the same time, the absence of direct transmission of light precludes the raising of any objection that could otherwise be made upon ethical grounds to the use of transparent glass.

15 The above-described recesses 8 are further used as pockets wherein are mounted as many lamps 13 (preferably incandescent electric) which provide the artificial light required to illumine the face of the dial by night, as well as the vault or apartment beneath. Reflective surfaces also are formed or placed, as at 14 and 15, above and by the side of each lamp on the walls of the pocket containing each, to cast a stronger light both 20 over the surface of the dial-plate and into the underlying vault or apartment.

25

Any appropriate advertising matter (verbal or pictorial) may be displayed upon or around the clock, and with or without the words "observatory time" hereinbefore mentioned. The clock alone might constitute a sufficient advertisement in some instances, but the addition of a name, a line of script or print, an illustration, and the like will hardly ever be considered surplusage while often it may be a valuable adjunct. Thus, the simple announcement "Safe deposit vaults," shown in Fig. 1, though it may not be needed to convey the 30 information that such vaults are situated on the same premises where the clock is located, to those already familiar with the surroundings, yet it may impart the information for the first time to many, and to all it will be 35 a constant reminder, as they catch a glimpse of the clock and pass on, or gaze upon its dial and perhaps stop long enough to set their time-pieces in accordance with its chronometric indications, that close at hand 40 there is open to them a reliable place where they can store away their money, jewelry, and other treasures.

Having now described my invention, what I claim, and desire to secure by Letters Patent of the United States, is:

1. An advertising clock with a non-transparent dial located in a light-giving aper-

ture, a casing therefor having a tortuous channel and means for holding said dial in a position whereby the view through the 60 aperture is obstructed and light is admitted beyond the dial through said tortuous channel.

2. A device of the character described comprising a casing provided with tortuous 65 passages set within an aperture in a sidewalk laid over a vault, an advertising clock therein positioned face up in the aperture and adapted to close the same save one or more of said tortuous passages permitting 70 the transmission of light beyond the clock, and a transparent glass cover common to both the clock and the aperture.

3. An advertising device comprising an apertured surface, a clock in the aperture, a 75 transparent glass cover for the aperture and clock therein, a ring adapted to prevent the direct passage of light through the glass cover beyond the clock's dial, said ring being cut away to form one or more pockets 80 in its inner side and under surface, and one or more lamps lodged in the pocket or pockets.

4. An advertising device comprising an apertured surface, a clock in the aperture, 85 a transparent glass cover closing the aperture at a suitable distance from the clock's dial, a ring extending inward over the edge of the dial and outwardly under the cover, said ring having one or more recesses in its 90 inner edge and under surface forming one or more pockets therein, a reflective surface in each pocket, and a lamp lodged in the pocket opposite said reflective surface.

5. An advertising device comprising a 95 suitably-apertured surface over a vault, an inwardly-flanged curb in the aperture, a transparent glass cover seated flush with the surface on the flange of said curb, a ring within the curb partly under its flange and 100 partly level therewith, a clock suspended in the aperture with its dial extending to the inner edge of said ring, lamps in cut-away portions of the ring, and reflectors for said lamps to direct the rays emanating 105 therefrom across the face of the clock's dial and into the vault beneath.

In testimony whereof I have signed my name to this specification in the presence of two subscribing witnesses.
